Letters Patent No. 2444, Date Sept. 25, 1860

Design for a Floor Oil Cloth Pattern

The Schedule referred to in these Letters Patent and making part of the same.

To all whom it may concern:

Be it known that I, Charles J. Meyer of the County of Bergen
County of Hudson, and State of New Jersey, have invented or produced a new
original and ornamental design or pattern for Floor Oil Cloth Carpets
and other Fabrics, and I do hereby declare that the accompanying drawing
hereto and designated as Print No. 5, fully represents said design and is sufficient
without further aid to enable any person skilled in the art to which it apper-
tains to repeat it for practical use. The colors and the arrangement of them may
in the use of this design, be varied to suit the views or fancy of the user or manu-
facturer of articles ornamental by said Design.

This design may be of any size or colors in kind, or number, or
in any contrast, or blending of colors in light and shade.

I claim as new and distinct to secure by Letters Patent of the United States
The Design for Floor Oil Cloths, Carpets &c. as shown and described.
